UNITED STATES PATENT OFFICE.

JULIUS BRENZINGER, OF MOUNT VERNON, NEW YORK, ASSIGNOR TO THE MAX AMS MACHINE COMPANY, OF MOUNT VERNON, NEW YORK, A CORPORATION OF NEW YORK.

ROLLER-BEARING.

1,177,300.

Specification of Letters Patent. Patented Mar. 28, 1916.

Application filed September 29, 1913. Serial No. 792,293.

To all whom it may concern:

Be it known that I, JULIUS BRENZINGER, a citizen of the United States, residing at Mount Vernon, in the county of Westchester and State of New York, have invented certain new and useful Improvements in Roller-Bearings, of which the following is a specification.

This invention relates to roller-bearings, with more particular reference to that class of bearings in which a plurality of cylindrical metal tubes are revolvably mounted on metal pins which are supported at their ends by annular head or end pieces, said head or end pieces being held in some manner in proper relation to each other so that the tubes or rollers are free to revolve on their respective pins.

The principal objects of the present invention include the provision of a roller-bearing the parts of which may be assembled easily and quickly, and in which the case hardening of the wearing parts of the bearing may be simplified; also the provision of a roller-bearing which will be extremely simple, very light in proportion to its strength, readily adaptable to various uses and susceptible of being manufactured rapidly and cheaply.

Still further objects and advantages of the present invention will be apparent to those skilled in this art, and will readily be understood from the following specification and claims and the annexed drawing, in which—

Figure 1 is a top plan view of a roller-bearing embodying my invention; Fig. 2 is a top plan view of the same, with the outermost member of the double end or head piece removed; Fig. 3 is a vertical section taken substantially on line X—X of Fig. 1, and Fig. 4 is a vertical section taken substantially on line Y—Y of Fig. 1.

Similar numerals of reference are employed to indicate corresponding parts throughout the several figures of the drawing.

Referring now to the drawing in detail, numeral 11 indicates a cylindrical tube of steel or other suitable metal, there being a plurality of these tubes of exactly similar shape and dimensions employed in each bearing, and nine of these tubes being shown

in the bearing illustrated by the accompanying drawing.

Numerals 12 indicate a pin of steel or other suitable metal which is preferably solid but may be tubular if preferred, is circular in cross-section and the diameter of which is somewhat less than the interior diameter of the tubes or rollers 11. In connection with a bearing embodying my invention in which nine rollers are employed, six of the pins upon which said rollers are mounted are exactly similar and have the same functions, said pins being of uniform diameter throughout and being cut off at both ends substantially at right angles to their longitudinal center lines. Pins 13 are longer than pins 12 and are provided at each end with a substantially square shoulder and an extension which is smaller in diameter than the pin itself and is preferably circular in cross-section, the main or body portions of pins 13 being of the same diameter as pins 12, so that rollers 11 fit loosely on pins 13, as well as on pins 12, and are revoluble thereon. Manifestly the relative numbers of pins 12 and pins 13 which may be used in a bearing embodying my invention may be varied as desired, but in bearings of the smaller sizes I have found it desirable to employ three of the pins 13.

Each of the two head or end pieces 14 and 15 in which the pins 12 and 13 are mounted consists of two parts, each part being in the form of a washer or ring. It has been my practice in the construction of bearings embodying my invention to make the inner head or end piece 14 somewhat thicker than the outer head or end piece 15, and both are punched or otherwise formed from sheet steel or other suitable metal. At equal intervals around ring 14, so as to be arranged symmetrically, and located on the center line of the circumferential face of the ring, are punched or otherwise formed the nine circular openings 16 of slightly larger diameter than that of the pins 12 and 13, so that said pins will fit closely in said openings but the fit will not be so tight as to necessitate the expenditure of force in putting the pins into place. The outer ring 15 has openings 17 punched or otherwise formed therein, said openings being spaced uniformly and located on the center line of the circumferen-

tial face of the ring, and being of such shape and dimensions as to adapt them to receive the reduced extensions of pins 13, the tightness of the fit being substantially 5 the same as that of pins 12 in openings 16.

In assembling one of my improved roller bearings, it is my practice to proceed as follows: Each of the rollers 11 is mounted upon its respective pin 12, said pins being 10 somewhat longer than the rollers, as shown in the accompanying drawing, so that each pin may project beyond its roller at each end of the latter; similarly each of the pins 13 has a roller mounted thereon, the length 15 of the body portion of each of said pins being substantially the same as that of pins 12. The projecting ends of pins 12 and 13 are then inserted into the openings 16 in rings 14, in such order that the rollers and 20 pins are arranged symmetrically around said rings, and the rings 14 are adjusted in such positions relative to each other that their faces are substantially parallel, the ends of pins 12 are substantially flush with 25 the outer faces of rings 14 and the reduced extensions of pins 13 project beyond the outer faces of both of the rings 14. Rings 15 are next put into place by fitting the openings 17 over the reduced extensions of 30 pins 13 and pressing rings 15 tightly into contact with rings 14. Having thus assembled the parts in the desired positions, the manufacture of the bearing is completed by upsetting the ends of the reduced extensions of pins 13 which project beyond the 35 outer faces of rings 15.

It is manifestly desirable in assembling my improved roller bearings in the manner just described, or otherwise, to lubricate 40 the pins 12 and 13 either prior to mounting the rollers 11 thereon or subsequently thereto; it is also manifestly desirable in assembling the parts to so adjust the positions of the end or head pieces (each comprising a 45 ring 14 and a ring 15) relative to each other that a slight clearance shall be left between the ends of rollers 11 and the inner rings 14 of the end or head pieces, thus leaving the rollers 11 free to turn with a minimum 50 of friction on pins 12.

In getting the parts of my improved bearings ready for assembling, it is my practice to case harden rollers 11, pins 12 and rings 14, but it is not my practice to harden pins 55 13 or rings 15, since it is manifestly unnecessary to harden rings 15 and although it would be possible to harden the body portions of pins 13, leaving the reduced extensions of said pins sufficiently soft so that 60 they may be upset or riveted, I have not found it necessary to harden pins 13 es-

pecially in the case of bearings which are of relatively small size and intended for relatively light service.

It will be apparent from the foregoing 65 description of my improved roller-bearing, and of the manner in which the parts are adapted to be assembled, that all of the parts may be manufactured rapidly and cheaply by automatic machinery or otherwise, all of the wearing parts may be case hardened in a very simple and inexpensive manner, machine work, fitting and the like on the parts is reduced to a minimum, lubrication of the rollers prior to or during assembly is facilitated and the assembling operation is rendered so simple that it may readily be performed either by hand or with automatic or other machinery at an extremely rapid rate and with a minimum of 80 expense.

Many modifications of minor details of my improved roller-bearing will doubtless readily suggest themselves to those skilled in this art, and I therefore do not desire to 85 limit my invention to the specific construction herein shown and described.

I claim as new and desire to secure by Letters Patent:

1. In a roller-bearing, the combination, 90 with two members each consisting of corresponding inner and outer annular plates, of a plurality of pins mounted in both plates of each end member and being provided with means for retaining said members and their component plates in fixed positions relative to each other, a plurality of pins mounted in the inner plates only of said members, and hollow rollers rotatably mounted on all of said pins between said 100 members.

2. In a roller-bearing, the combination, 105 with two end members each consisting of inner and outer plates, of a plurality of pins upon which said rollers are rotatively mounted, some of said pins extending through both plates of each end member and being provided with means for retaining said members and their component plates in a fixed position relative to each other, 110 and the remaining pins extending through the inner plate only of each end member and being retained in position by said outer plates, and hollow rollers rotatably mounted on all of said pins between said members. 115

In testimony of the foregoing, I have hereunto set my hand in the presence of two witnesses.

JULIUS BRENZINGER.
